EDWARD R. MOFFITT, OF SAN FRANCISCO, CALIFORNIA, ASSIGNOR TO IMPERIAL GAS ENGINE CO., OF SAN FRANCISCO, CALIFORNIA, A CORPORATION OF CALIFORNIA.

ELECTRIC SPARKING DEVICE FOR GAS-ENGINES.

No. 878,412.

Specification of Letters Patent.

Patented Feb. 4, 1908.

Application filed March 13, 1907. Serial No. 362,197.

To all whom it may concern:

Be it known that I, EDWARD R. MOFFITT, a citizen of the United States of America, resident of the city and county of San Francisco and State of California, have invented 5 new and useful Improvements in Electric Sparking Devices for Gas-Engines, of which the following is a specification.

This invention relates to improvements 10 made in devices for generating an electric-spark in the cylinder of a gas-engine, to fire the charges of explosive mixture. Devices of this character generally comprise two electrodes in open circuit with a source of electricity and operated from some moving part 15 of the engine in time with the movements of the piston, to generate a spark between their contact-points or surfaces every time the two electrodes are caused to touch and separate. 20 But being of necessity located in the explosion chamber, or in a compartment that communicates directly with the chamber in which the charge is exploded, the electrodes soon become carbonized or coated with the 25 non-conducting matter deposited on their contact-surfaces, and are rendered uncertain or defective in operation; so that it is found necessary to clean the surfaces from time to time by removing the electrodes from the 30 cylinder, or by opening the chamber or compartment in which they are inclosed, so as to give access to the contact-surfaces, that the operation of scraping or cleaning them may be carried on in the chamber.

35 The present invention has for its object to enable the contact-points or surfaces of electrodes of this character to be readily cleaned of the deposits and restored to effective working condition without opening the 40 chamber in which they are inclosed, and without removing them from the chamber; and to that end and purpose the invention consists essentially in so forming or constructing one of the electrodes that it is movable 45 by hand from the outside of the cylinder or the explosion chamber, and in addition to the motion imparted to it from the engine by which the spark - generating surfaces are brought alternately in working-contact and 50 separated, the contact - surfaces can be rubbed together or caused to scrape and brighten each other by the simple operation of moving one of the electrodes from the outside of the cylinder.

55 The nature of the said invention and the

manner in which I proceed to produce, apply and carry out the same will be explained at length in the following description, in which the accompanying drawings illustrating the application of my said invention to one type 60 or construction of electric-sparker are referred to by figures and letters.

Figure 1 of the drawing is a plan or top-view of an electric sparker for a gas-engine embodying my invention, the device being of 65 the type of electric-sparker composed of two electrodes, one of which is stationary, and the other is partially rotatable. Fig. 2 is a vertical sectional-view taken longitudinally through the center of the device, and showing 70 a portion of the shell of the chamber or the cylinder in which it is inserted and fixed by screws. Fig. 3 is an end-elevation looking from the right side of Fig. 1; and Fig. 4 is a similar elevation looking from the left side 75 of Fig. 1, but with the long coiled -spring omitted from the stem of the movable electrode.

These figures of the drawing illustrate the parts and features of the spark-generating 80 device itself, but do not show the mechanism by which the electrodes are caused to make and break contact from a moving part of the engine.

The electrode *a* is the fixed or stationary 85 contact. It is insulated from the surrounding metal of the plug or body *b*, by the bushing *c* of insulating material, and it is made the terminal of one pole of the generator from which current is supplied by means of a 90 conducting wire *x* attached to the end outside. The other electrode *d* is movable axially in its socket or bearing in the plug, and its movement on its axis is a partially 95 rotating one, the extent of which is sufficient 95 to bring its contact-piece or foot *e* against the contact-surface of the stationary electrode.

The foot *e* on the end of the stem *d* is held 100 normally out of contact with the electrode *a* and is separated from it after each contact by the torsional force of the coiled-spring *g* surrounding the stem. The movement that brings the two electrodes in contact to close the circuit is effected by a partial rotation of 105 the stem through the medium of a short arm or tappet *h*, on a sleeve *k* loose on the stem, and the latter being movable on the sleeve *k* is also connected to it by the spring *g*; one 110 end of which is secured to the stem *d* by

means of a collar or short sleeve *m* on the head of the stem *d*, while its opposite end is secured to the sleeve *k*.

The tappet is the part that engages the cam or other part of the mechanism which, by a rotary or oscillating motion, gives the required movement to the sleeve *k*, and through that part moves the stem *d* in the proper direction to bring the contact-piece *e* against the opposite electrode *a*.

10. The mechanical means for moving the stem in opposition to the torsional force of the spring *g* is not illustrated or described, for the reason that electric sparking-devices in which one electrode is brought against the other by an oscillating or a partial rotary movement, are operated from some moving part of the engine in various ways, for example, by a cam, or a rocking-arm or lever 15 acting against the tappet to move the stem against the force of the spring at the required intervals. The manner of operating the movable electrode is too well-known to those familiar with the art to require explanation.

20. A stop-pin *p* on the plug limits the throw of the tappet in one direction, and the end of the sleeve is locked to the end of the sleeve above it when the tappet is moved in the opposite direction, thereby giving partial rotation to the stem. The parts *k*—*m* are formed with projections or shoulders on, their adjoining ends, that serve to lock one to the other in the forward throw of the tappet; and at the same time permit an adjustment axially of the stem by loosening the upper sleeve or member and turning the stem in it. For that purpose the sleeve is fastened on the stem *d* so as to be loosened and 35 turned as occasion may require, and in the present construction the parts are fastened by a pin *d'* inserted through the head of the upper member and the stem, as seen in Fig. 1. In addition to the movement by which it is 40 caused to make and break contact, as before described, the movable electrode is so fitted or adapted that it can be moved longitudinally in the hole or socket in the plug, simply by grasping the head of the stem and giving it a short movement in the direction of its longitudinal axis. This operation has the effect of cleaning the contact-surfaces of the two electrodes by rubbing one against the other, and is performed from time to time 45 by turning the stem by hand so as to bring one electrode against the other, and then moving the stem with a short reciprocating motion while the contact-surfaces are pressed against each other.

50. In the present construction in which I have embodied my invention, a coiled-spring *s* is interposed between the top of the plug and the end of the sleeve *k*, the function of which spring is to hold the stem normally in its elevated position, or so as to maintain the

55. electrode *e* in the required plane to act against the contact-surface of the opposite electrode. This spring *s* being compressed in the downward or inward thrust of the stem serves to return or elevate that part 70 when the pressure of the hand in working it is removed. The spring *s* surrounds the neck *t* through which the stem extends above the face of the plug. The neck also forms a stop to arrest the thrust of the stem. 75 The reciprocating movement of the stem within the limits which are controlled in one direction by this stop and in the opposite direction by a shoulder on the bottom of the stem, is of sufficient length or extent to bring 80 the entire contact-surfaces that are in action on both electrodes in rubbing contact with each other to effectively clean them.

85. Provision is made for changing the acting surface of the stationary electrode from time to time as it becomes burned or worn, by using a pin or contact-piece of the well-known helical shape as illustrated at *a'* in Fig. 3. The pin *a* is fixed in place by means of nuts *w* on the threaded end of the bushing on the outside of the plug. A fresh contact-surface on the pin *a* is presented to the opposite electrode by loosening the nuts and turning the pin in the bushing. As thus constructed and arranged for operation, it will be seen 90 that the coacting surfaces of both electrodes can be cleaned as often as desired without removing them from the engine, or opening the chamber or compartment in which they are inclosed; also, that the operation of cleaning the electrodes can be carried on from the outside of the chamber without disturbing the position or adjustment of the parts or disconnecting the mechanism by which the electrodes are actuated to make and break 95 the circuit.

100. In the present construction the parts are all mounted on or contained in the plug, which is secured in place on the shell of the explosion chamber by lag-screws *z*.

110. Having thus described my invention, I claim:

115. 1. In an electric sparking device adapted for use in gas engines, the combination of a stationary electrode, a rotatable stem carrying the contact piece that constitutes the movable electrode, a tappet piece loosely fitted on the stem so as to be rotatable relative thereto, a sleeve also loose upon the stem, the sleeve and tappet piece being provided with locking or interengaging shoulders, arranged to permit a rotative movement 120 of one relative to the other, means for securing the sleeve fast to the stem in one or another position of rotative adjustment, and a spring connected at its opposite ends respectively with the tappet piece and the said sleeve, substantially as set forth.

125. 2. In an electric sparking-device for a gas engine, the combination of a plug, the sta- 130

tionary electrode therein, a stem free to oscillate about its axis and also movable longitudinally in the plug and carrying a contact-piece on the end inside the explosion-
5 chamber of the engine, a tappet-piece loosely fitted on the stem and rotatably movable thereon, a coiled spring connected at one end with the stem, its other end being con- nected with the tappet-piece, and a coiled spring interposed between the said tappet- 10 piece and the plug, substantially as described for operation as set forth.

EDWARD R. MOFFITT.
